REFRIGERATING APPARATUS

Earl F. Hubacker, Highland Park, Mich., assignor to Borg-Warner Corporation, a corporation of Illinois

Application November 27, 1935, Serial No. 51,760

15 Claims. (Cl. 230—145)

This invention relates to refrigerating apparatus and has reference to an improved form of compressor construction which is particularly adapted for use in refrigerating systems of the type wherein a refrigerating medium is circulated through a closed system and is successively compressed in a gaseous state, condensed into a liquid and thence expanded by evaporation at a relatively low pressure.

10 The compressor is of the type illustrated in Letters Patent No. 2,028,824, filed October 9, 1933, in the name of John C. Buchanan, for "Refrigerating system", and dated January 28, 1936.

15 The compressor structure disclosed herein constitutes an improvement over that disclosed in said Buchanan patent and relates particularly to certain refinements in construction which tend to improve the efficiency of the compressor, which reduces wear on certain parts thereof, and which 20 eliminates certain undesirable noises which sometimes occur in compressors of the type referred to under certain conditions of operation, such as "blade clicking".

25 A principal object of the invention thereof is to provide an improved form of rotary compressor construction which is more quiet in operation, and in which, the tendency of certain of the parts thereof to wear has been minimized.

Another object of the invention is to provide an 30 improved form of compressor construction which is particularly adapted for use in a refrigerating system.

Another object of the invention is to provide a 35 novel form of blade construction for compressors of the type herein disclosed.

Other objects and advantages will be apparent 40 from a consideration of the following specification taken in conjunction with the accompanying drawings of which there are 2 sheets; and in which:

Fig. 1 is a sectional view through a compressor and illustrating a preferred embodiment of the invention;

Fig. 2 is a sectional view taken along the line 45 2—2 of Fig. 1 and illustrating in elevation the operating parts of the compressor;

Fig. 3 is a sectional view along the line 3—3 of Fig. 1, looking in the direction of the arrows;

Fig. 4 is a sectional view taken generally along the line 4—4 of Fig. 3 illustrating the details of the compressor discharge valve;

Fig. 5 is a fragmentary view of a detail taken in a plane along the line 5—5 of Fig. 1, looking in the direction of the arrows;

Fig. 6 is a perspective view of the compressor blade; and

Fig. 7 is a view similar to Fig. 2 of the operating parts of the compressor but with the parts of the compressor illustrated in a position 180° from the position in which the parts are illustrated in Fig. 2.

The compressor mechanism, in general, may be said to comprise a cylinder, an eccentric oscillatable about the center of said cylinder, a rotor or 10 sleeve carried by the eccentric, and a blade reciprocable in a radial slot formed in the wall of the cylinder and biased into engagement with the outer surface of the rotor, all of which parts are submerged in a bath of oil for lubrication 15 purposes when such compressor is employed for the purpose of compressing vaporous refrigerant.

In the drawings such pumping mechanism is disclosed in connection with a compressor, the operating shaft of which extends through an 20 opening in a wall thereof and which opening is provided with a seal to prevent the escape of lubricant and refrigerant from the compressor, the shaft externally of the compressor being adapted to be connected to a moving source of 25 energy to be operated thereby.

A bearing block 10 provided with a base 12 is provided with a bearing 14 in which a shaft 16 is journaled, said shaft projecting at one end thereof from the bearing block 10, and having a seal, 30 indicated generally at 18, operatively associated with such end of the shaft for preventing the escape of refrigerant and lubricant from the compressor. A dome 20 is secured to the face of the bearing block 10 in such a manner as to provide 35 a gas tight joint therewith, and is adapted to provide internally thereof a chamber forming a lubricant and refrigerant reservoir 22.

The face 24 of the bearing block is provided with an annular flange 26, there being provided 40 in the face of the bearing block within the area determined by the flange 26, a recess 28 which is partially closed by a plate 30 which lies flat against the face of the bearing block and within the flange 26 which serves as a locating member 45 for the plate 30.

A rigid cylinder block 32 has one face thereof disposed against the plate 30 and has disposed against the other face thereof, a somewhat similar plate 34 which is covered by an end cap 36, the bearing block 10 being provided with a series of threaded openings 38 which are adapted to receive the threaded ends of a series of stud bolts 40 which pass through aligned openings in the plates 30 and 34, the cylinder block 32 and the 55

end cap 36, all of which parts are thereby rigidly secured to the bearing block 10. The end plate 34 and the cap 36 provide therebetween a discharge valve chamber and are assembled and held together initially by a pair of bolts 39.

The side faces of the cylinder block 32, which are in contact with the faces of the plates 30 and 34 as well as the faces of such plates, are smoothly finished and are disposed parallel, and there is provided within the space defined by the cylinder block 32 and the end plates 30 and 34, a working chamber 44 through which the shaft 16 extends, the shaft within such chamber being provided with an integral eccentric portion 46. The end cap 36 is formed to provide a bearing 48 for the end of the shaft 16, and a washer 50 is secured to the end of the shaft by a stud bolt 52 which washer bears against the end of the bearing 48 to provide a thrust bearing for the shaft 16.

The inner surface of the cylinder block 32 is arranged concentric with respect to the axis of the shaft 16 and is smooth and continuous except for an inlet opening 54 and a radial slot 56 extending transversely of the cylinder block 32 and between the end plates 30 and 34. The end plates 30 and 34 are provided with central openings therein through which the shaft 16 extends and through which openings lubricant may be supplied to the working parts of the compressing mechanism.

A rotor or sleeve 58 is freely disposed about the eccentric portion 46 of the shaft. The rotor or sleeve 58 is of slightly less length axially than the distance between the end plates 30 and 34 and is adapted to form a working seal therewith, lubricant under pressure being supplied to the inside of the rotor through the central openings in the end plates 30 and 34 whereby the abutting surfaces of the rotor and the end plates are lubricated. The rotor 58, when assembled on the eccentric 46 and upon rotation of the shaft 16, is adapted to oscillate or gyrate within the working chamber 44, the shortest radial distance between the most external portion of the eccentric 46 and the inside wall of the cylinder block 32 being slightly greater (in the neighborhood of several ten thousandths of an inch) than the radial thickness of the rotor 58, so that the rotor does not contact the cylindrical wall of the cylinder block 32, a film of lubricant upon the cylindrical wall of the cylinder block 32 and the surface of the rotor 58 being relied upon to form a seal between the rotor and the cylinder wall.

A blade 62, shown in perspective in Fig. 6, is mounted for reciprocation within the radial slot 56 and is backed by a pair of springs 64 which bear against the shoulders 66 on the blade, and which springs are secured in position by a bracket 68' which is secured by means of a plurality of screws 70 to a portion of the cylinder block 32. The blade 62, it will be observed, is provided on one end thereof with a flange 68 which forms a toe. The end of the blade and the flange 68 form a boot, the edge 68 thereof being designated as a heel. The underside of the toe or flange portion 68 of the boot is adapted to engage the outer surface of the sleeve 58 for separating the space within the working chamber 44 on opposite sides of the blade 62. The radial slot 56 in the cylinder block 32 is enlarged at the inner end thereof to provide a space 70 for accommodating the toe 68 of the blade during the portion of the stroke in which the rotor 58 travels from the position in which it is illustrated in Fig. 2, to the position in which it is illustrated in Fig. 7. A discharge

slot 72 extending transversely of the cylinder block is in communication with the space 70 and leads to a discharge opening 74 in the plate 34 which has associated therewith a discharge valve 76. A restricted communication between the discharge slot 72 and the working chamber 44 is provided by means of an angularly disposed passageway 78 formed in the end plate 34. Just before the rotor 58 completes a stroke, the passageway 78 operates to place the discharge slot 72 in communication with the suction side of the rotor which tends to relieve the pressure in the discharge slot at such time.

In the normal operation of the pumping mechanism, a certain amount of lubricant passes through the pump and on account of the fact that such lubricant is in liquid form and hence incompressible, some noise, which is made thereby or which may be due to the sudden drop in pressure in the discharge slot 72, may be eliminated by use of the restricted passageway.

During the operation of the compressor, vaporous refrigerant is drawn in the cylinder chamber 44 through the inlet opening 54 and is compressed therein by the rotor 58 upon oscillation thereof and between the rotor 58 and the blade 62. The blade 62 follows the rotor and hence reciprocates within the slot 56. The gas after compression within the cylinder chamber 44 is discharged past the discharge valve 76 and through the conduit 80 into the upper portion of the chamber 22. Refrigerant may escape from the upper end of the reservoir 22 through the tube 84 which leads to the exterior of the compressor and thence to an evaporator.

Within the recess 28 and secured to the shaft 16 a counterweight 86 is disposed which, in addition to balancing the shaft, operates as a lubricant pump for circulating lubricant through the passageway 88, the space around the seal 18, the passageway 90 and through a series of slots 92 in the bearing block affording communication between the recess 28 and the reservoir 22. The cap 36 is provided with a plurality of openings 94 which communicate with the central opening in the end plate 34 and afford a passageway whereby the lubricant may communicate with the interior of the rotor 58. It will be understood the reservoir 22 is charged with sufficient lubricant so that the level thereof is above the blade 62. During operation the blade 62 separates the low pressure side of the compressor from the high pressure side thereof and is biased to follow the rotor 58 by the springs 64 and the pressure within the reservoir 22 to which the rear face, indicated generally at 98, is exposed. The lubricant and the refrigerant within the reservoir 22 is under the discharge pressure of the compressor since the compressor discharges into the reservoir 22.

The portion of the blade 62 within the working chamber 44 is subject to the difference in pressure of the gas on the high and low pressure sides of the pump which, unless counteracted will tend to cause the blade 62 to bind in the slot 56. The tendency of the blade to bind in the slot under the pressure of the gas in the high pressure side of the compressor is substantially balanced by the head pressure acting on the rear face 98 of the blade, the springs 64 acting on the rear face of the blade and the pressure on the high pressure side of the compressor to which that portion of the toe 68 of the blade is exposed between the flat 100 on the high pressure side of the blade and the point of contact between the toe of the blade and the rotor 58. It will be observed from an inspection of Figs. 2 and 7,

which illustrate the parts of the compressor in positions 180° apart, that the point of contact between the toe of the blade 62 and the rotor 58 moves back and forth along the under side 5 of the toe of the blade 62 but in no case is it transferred past the central axis of the blade onto the portion thereof opposite the flange portion. The blade will be observed to be so relieved upon its rotor contacting or inner surface that it 10 never contacts the rotor at a point more central than is indicated in Fig. 7.

In the position in which the parts are illustrated in Fig. 2, the point of contact between the toe of the blade and the rotor is near its extreme 15 position where the effective area of the toe 68 exposed to the high pressure side of the compressor is the greatest, and in Fig. 7, the point of contact between the toe 68 and the rotor 58 is at a position where the effective area of the 20 toe 68 exposed to the high pressure side of the compressor is practically the smallest. It will thus be apparent that the effective area of the toe 68 exposed to the high pressure side of the compressor varies with the position of rotor 58 25 and also varies with the pressure differential between the high and low pressure sides of the compressor. This design of a blade has the effect 30 of balancing the various forces acting on the blade so as to eliminate any tendency thereof to bind whereby wear of the material of the cylinder block which defines the blade slot 56 is largely 35 eliminated.

During the off cycle of the condensing unit when the compressor is at rest, the head pressure within the reservoir 22 causes seepage of lubricant into the low and high pressure sides 35 of the compressor so that upon starting the compressor after the same has been idle for a period of time, the lubricant which has seeped into the 40 compressor is discharged therefrom during the first couple of revolutions thereof. As the discharge orifice from the compressor is designed primarily for the passage of a vaporous medium and not for a liquid medium, considerable restriction to the escape of lubricant from the 45 compressor is offered during its initial movement with the result that relatively high pressures are built up within the high pressure side of the compressor immediately after starting. This high 50 pressure is utilized for aiding in causing the blade to follow the rotor 58 as the toe portion 68 provides an effective area exposed to the high pressure side of the compressor which aids in holding the blade 62 in contact with the rotor 58. In this manner blade clicking is eliminated. 55 Blade clicking is caused by the binding of the blade due to the high pressure differential on opposite sides thereof and the ensuing separation and contact of the blade with the rotor as the 60 pressure differential is built up and relieved. The under face 104 of the boot of the blade is on a line tangent to the radius at the point of contact between the parts when they are in approximately the position illustrated in Fig. 7.

The axis of the shaft 16 may be offset from the center about which the inner surface of the cylinder block 32 is formed up to one thousandth of an inch (.001") in the direction of the arrow 43 to compensate for the effect of the pressure 65 differential between the high and low pressure sides of the compressor, which pressure differential constrains the rotor 58 toward the wall of the cylinder block 32 principally in that portion of the travel of the rotor 58 between the position 70 in which it is illustrated in Fig. 7 and approxi-

mately 90° therebeyond in its direction of rotation. The clearance between the shaft 16 and its bearings, and the clearance between the eccentric 46 and the rotor 58 permit relatively small displacements of the rotor 58 with respect to the 5 axis of rotation of the shaft 16, and it is desirable to offset the shaft 16 so as to prevent the rotor from being forced into rubbing contact with the internal wall of the cylinder block 32.

While the invention has been described with some detail, it is to be understood that the description is for the purposes of illustration only and is not definitive of the limits of the inventive idea. The right is reserved to make such changes in the details of construction and arrangement of parts as will fall within the purview of the attached claims.

I claim:

1. A rotary compressor comprising a cylinder block providing a cylindrical pumping chamber, 20 a rotor oscillatable in said chamber, a blade reciprocably mounted in the wall of said cylinder block and cooperable with said rotor for separating the high and low pressure sides of said compressor, spring means constraining said blade into 25 engagement with said rotor, means whereby the rear face of said blade may be subject to the discharge pressure of said compressor, and a means for subjecting the blade to the pressure on the high pressure side of the compressor for constraining said blade to follow said rotor upon oscillation thereof, the relationship, formation and construction of the blade and rotor being such that all contact between these two parts occurs upon that side of the central blade axis toward 30 the high pressure side of the compressor.

2. A rotary compressor comprising a cylinder, a rotor oscillatable in said cylinder, a blade reciprocably mounted in the wall of said cylinder and exposed to the discharge pressure of said compressor externally thereof, and spring means constraining said blade into engagement with said rotor for separating the high and low pressure sides of said compressor, said blade internally of 40 said cylinder being provided with a laterally extending flange on the high pressure side thereof, the end of the flange extending farther toward the center of the cylinder than other portions thereof and which flange is engageable with said rotor upon oscillation thereof, the point of engagement between said rotor and said flange upon oscillation of said rotor being movable for varying the effective area of the flange exposed to 45 the low pressure side of the compressor but always occurring at a point laterally offset with respect to the central blade axis toward the blade flange.

3. A compressor comprising a cylinder affording a pumping chamber, a pressure chamber surrounding the cylinder adapted to receive the discharge from the pumping chamber, a rotor mounted for oscillation within said cylinder, said cylinder being provided with a slot in a wall thereof, a blade reciprocably mounted in said slot extending into said pumping chamber and exposed 60 at the rear face thereof to said pressure chamber, said blade within said pumping chamber being provided with a laterally extending flange engaging said rotor for separating the high and low pressure sides of the compressor within the pumping chamber, and spring means constraining said blade for causing said flange to follow said rotor upon oscillation thereof, said flange being disposed only on the side of the blade exposed to 65 the high pressure side of the compressor, the 70 75

engagement between the blade and the rotor occurring always between the flange and the rotor.

4. In a compressor, a cylinder providing a pumping chamber internally thereof, a rotor oscillatable in said pumping chamber, said cylinder being provided with a slot in the wall thereof and in communication with said pumping chamber, a blade reciprocably mounted in said slot and provided with a laterally extending flange within the pumping chamber, said flange being engageable with said rotor for separating the high and low pressure sides of the compressor, and spring means constraining said blade for holding said flange thereof in contact with said rotor upon oscillation thereof, said flange extending from the side of the blade exposed to the high pressure side of the compressor, the rotor contacting surface of the blade being so formed that the blade heel and rotor may never contact one another.

5. A rotary compressor comprising a cylinder, a rotor oscillatable in said cylinder, a blade reciprocably mounted in the wall of said cylinder and exposed to the discharge pressure of the compressor externally thereof, and spring means constraining said blade into engagement with said rotor for separating the high and low pressure sides of said compressor, said blade internally of said cylinder being provided with a laterally extending flange only on the high pressure side thereof and which flange is engageable with said rotor upon oscillation thereof, said flange providing an effective area exposed to the high pressure side of the compressor which varies in accordance with the pressure differential between the high and low pressure sides of the compressor whereby said blade is constrained to follow said rotor, the parts being so proportioned and arranged with respect to one another that the variation in effective area at no time is so great as to expose a larger area of the rotor contacting surface of the flange to high pressure than is exposed upon the surface of the flange opposite the rotor contacting surface.

6. A rotary compressor having a cylinder and a rotor mounted for oscillation therein, a blade engaging the rotor for separating the high and low sides of said compressor mounted to slide in a wall of said cylinder, said blade having a flange at its rotor engaging end which extends only toward the high pressure side of the compressor, the rotor contacting surface of which forms an obtuse angle with the blade, said angularity being so related to the diameter and eccentricity of the rotor as to prevent contact between the rotor and blade upon that side of the central blade axis opposite to said flange.

7. A rotary compressor having a cylinder and a rotor mounted for oscillation in said cylinder, said rotor comprising a sleeve mounted to rotate upon an eccentric and progressively to be associated with said cylinder, a blade mounted to slide in a slot in said cylinder and having a flanged portion laterally projecting beyond the body of the blade toward the discharge side of the compressor, said flange being spring urged into contact with said sleeve and having its external portion exposed to high pressure said contact at all times being between said flange and said rotor.

8. A rotary compressor comprising a cylinder, a rotor mounted eccentrically upon a shaft for oscillation in said cylinder, and a blade mounted in a slot in said cylinder for separating the high and low sides of said compressor, the axis of said shaft and about which it rotates being permanently displaced from the center of said cylinder

a distance sufficient to compensate for bearing clearances in the general direction of the point of highest compression within the cylinder.

9. A rotary compressor comprising a cylinder, a shaft mounted to extend into said cylinder, said shaft having an eccentric thereon within the cylinder, a rotor mounted upon the said eccentric, and a blade mounted in a slot in said cylinder for separating the high and low sides of said compressor, the axis of said shaft and about which it rotates being permanently displaced from the center of said cylinder a distance sufficient to compensate for clearances in the general direction of the point of highest compression within the cylinder.

10. A rotary compressor comprising a cylinder, a rotor mounted eccentrically upon a shaft for oscillation in said cylinder, and a blade mounted in a slot in said cylinder for separating the high and low sides of said compressor, the axis of said shaft and about which it rotates being permanently displaced from the center of said cylinder a distance not greater than one thousandth of an inch in the general direction of the point of highest compression within the cylinder.

11. A rotary compressor comprising a cylinder, a rotor mounted eccentrically upon a shaft for oscillation in said cylinder, and a blade mounted in a slot in said cylinder for separating the high and low sides of said compressor, said shaft being mounted in said cylinder with its axis of rotation permanently displaced from the center of the cylinder toward the point of highest compression within the cylinder a distance sufficient to compensate for bearing clearances.

12. A rotary compressor comprising a cylinder block provided with a slot in the wall thereof, a rotor mounted for oscillation within said cylinder block, and a blade mounted for reciprocation within said slot, and provided with a laterally extending flange portion for engaging said rotor, and means constraining said blade for holding said flange portion thereof in engagement with said rotor upon oscillation thereof, said flange extending further toward the center of the cylinder than other portions of the blade, and the rotor, blade and flange being so positioned and dimensioned that the engagement between the blade and the rotor takes place at all times upon the flange portion of the blade.

13. A rotary compressor comprising a cylinder block affording a cylindrical pumping chamber, a rotor mounted for oscillation within said pumping chamber, said cylinder block being provided with a slot in the wall thereof, a blade slidably mounted within said block and provided with a flange portion for contacting said rotor whereby to divide the high pressure side of the compressor from the low pressure side thereof, the rotor-presented surface of the flange forming an obtuse angle with the central axis of the blade, and means constraining said blade for holding the flange portion thereof in engagement with the rotor upon oscillation thereof, the point of contact between the flange portion of the blade and the rotor being such as to provide an effective area of the flange portion exposed to the high pressure side of the compressor for assisting in holding the blade in contact with the rotor upon oscillation thereof, said blade and rotor contact lying constantly upon the rotor-presented surface of the blade which lies between the central axis of the blade and the tip of the flange portion.

14. A rotary compressor comprising a cylinder block provided with a cylindrical pumping cham-

ber, a rotor oscillatable in said chamber, said cylinder block being provided with a slot in the wall thereof, a blade reciprocable in said slot and adapted to engage said rotor for dividing the high and low pressure sides of said compressor, an inlet to said pumping chamber on one side of said blade, a discharge from said pumping chamber upon the other side of said blade, said blade outside of said pumping chamber being subject to the discharge pressure of said compressor, and spring means constraining said blade into engagement with said rotor, said blade internally of the pumping chamber being provided with a boot portion which is engageable with said rotor, the surface of the boot portion which is presented to the rotor being angularly so arranged with respect to the central axis of the blade as substantially to prevent contact between the rotor and such surface of the boot portion adjacent the heel thereof, said boot portion being so arranged as to provide an area thereof which is exposed to the high pressure side of the compressor whereby the pressure on the high pressure side of the compressor operates to hold said boot portion of said blade in sealing engagement with said rotor.

15. Refrigerating apparatus comprising a compressor having a cylinder providing a pumping chamber, a rotor oscillatable in said cylinder, a blade slidably mounted in a slot in the wall of said cylinder and extending into the pumping chamber, said blade being provided with a lateral flange upon one side of the blade and exposed to the high pressure side of the compressor, said flange being engageable with said rotor for separating the high and low pressure sides of the compressor, spring means constraining said blade to follow said rotor upon oscillation thereof, and means whereby the rear face of the blade externally of the cylinder is exposed to the discharge pressure of the compressor, the construction and arrangement of the rotor, blade and flange being such that the contact between the flange and rotor under the influence of said spring means and said external discharge pressure produces a moment in the direction of the center of the cylinder on the blade which tends to rotate the same about its point of contact between the flange and the rotor.

EARL F. HUBACKER. 25
